CLAIM

The ornamental design for the food storage container, as shown and described.

DESCRIPTION

FIG. 1 is a front perspective view of the food storage container with the environment of a lid attached to the food storage container;

FIG. 2 is a front perspective view of the food storage container with the lid removed for ease of illustration;

FIG. 3 is a front view thereof;

FIG. 4 is a rear view thereof;

FIG. 5 is a left view thereof;

FIG. 6 is a right view thereof;

FIG. 7 is a top view thereof;

FIG. 8 is a bottom view thereof;

FIG. 9 is a bottom right perspective view of the food storage container; and,

FIG. 10 is a cross-section of a lower portion of the food storage container.

The even-dash broken lines in the drawings showing a removable lid in FIG. 1 represent environment and form no part of the claimed design. The dash-dot broken lines represent the cut line of the section view. All other broken

(Continued)

lines represent portions of the food storage container and form no part of the claimed design.
